H. GOODWIN

CARTRIDGE FUSE

Filed June 6, 1921

INVENTOR:
Hall Goodwin.

By W. B. Stevens & Co.
ATTORNEYS.

UNITED STATES PATENT OFFICE.

HALL GOODWIN, OF CHICAGO, ILLINOIS.

CARTRIDGE FUSE.

Application filed June 6, 1921. Serial No. 475,354.

To all whom it may concern:

Be it known that I, HALL GOODWIN, a citizen of the United States, residing at Chicago, in the county of Cook and State 5 of Illinois, have invented new and useful Improvements in Cartridge Fuses, of which the following is a specification.

This invention relates to electrical fuses of the cartridge type, and its object is to 10 provide a simple and efficient holder for the fusible element which enables said element to be readily removed for renewal when it is blown.

The invention also has for its object to 15 provide a simple means for guarding against overloading of the fuse.

The objects stated are attained by means of a novel combination and arrangement of parts to be hereinafter described and 20 claimed, and in order that the same may be better understood, reference is had to the accompanying drawing forming a part of this specification.

In the drawing, 25 Fig. 1 is an elevation of the device; Fig. 2 is a central longitudinal section thereof; Figs. 3 and 4 are enlarged cross-sections on the lines 3—3 and 4—4 of Fig. 2; Fig. 5 is a perspective view of a portion of the 30 device, and Fig. 6 is a plan view of the fusible element.

Referring specifically to the drawing, the body of the fuse holder is an elongated tubular casing which is made in two longitudinal 35 and similar sections denoted by the reference characters 5 and 6, respectively, the same being constructed of fiber or other non-conducting material. The ends of this casing are closed by being fitted with heads of 40 brass or other conducting material, said heads being also made in two sections conforming to the casing sections. The head portions of the section 5 are shown at 5^a, and those of the section 6 at 6^a. Tongue- 45 and-groove joints 7 are made between the longitudinal edges of the casing sections 5 and 6. This structure produces a tight joint to prevent the escape of the flame when the fuse blows. However, the joint is not air-tight and hence the escape of fumes from 50 the casing when the fuse blows is not prevented. The head sections 5^a and 6^a fit over the ends of the casing sections 5 and 6, and they will be die cast and provided on the 55 inside with pins 8 to enter holes in the casing sections for securing said parts in as-

sembled relation, the pins being riveted on the inside of the casing sections. The tongue-and-groove joints 7 are not continued through the head sections 5^a and 6^a, the contiguous edges thereof being left smooth. However, the sections 5^a have edge lugs 9 to seat in edge recesses 10 in the sections 6^a, and thereby prevent the casing sections 5 and 6 from shifting lengthwise with respect 60 to each other. These lugs and recesses at the respective ends of the casing are on diametrically opposite sides so as to enable either section 5^a to be placed opposite either section 6^a, and also to enable said sections 70 5^a and 6^a, respectively, to be cast alike.

Over the headed ends of the casing hereinbefore described are removably fitted terminal caps 11 and 12, respectively, which are made of brass or other conducting material. The sides of these caps fit snugly against the sides of the heads composed of the sections 5^a and 6^a to obtain an electrical connection, and to assure such connection, the ends of the caps may be provided with 80 contact screws 13 which are threaded through said ends to come into positive contact with the ends of the fusible element to be presently described. These screws are headed on the inside of the caps, as shown at 13^a, so that they cannot get lost by screwing out of the cap ends. 85

The terminal caps 11 and 12 are locked against endwise separation from the headed ends of the casing, by projecting side pins 14 carried by the head sections 5^a and 6^a and seating in angular slots in the sides of the caps. These slots extend lengthwise of the caps from their inner ends, for a short distance, as shown at 15, and then extend laterally, as shown at 15^a. In applying the caps they are placed so that the inner portions 15 of the slots are in line with the pins 14, whereupon the caps can be slid inwardly, and when the pins reach the lateral branches 15^a the caps are given a turn to seat the pins therein, which completes the coupling operation. It will be noted that the lateral portions 15^a of the slots are inclined in a direction to draw the caps inwardly when the pins 14 pass along the same. It will also be noted that the locking pins of the caps 11 and 12 are not diametrically opposite each other, the pins on the head sections 5^a being centrally located, whereas the pins of the corresponding sections 6^a are off center, about 45 degrees. The 100 105 110

- pins of the sections 6^a are also offset relative to each other. This arrangement of the pin assures proper assembly of the caps so that the contact screws will always come opposite the ends of the fusible element.
- 5 The casing hereinbefore described encloses a fusible element in the form of a strip or ribbon 16 carried by a shell 17 of non-combustible and non-conducting material.
- 10 This shell is filled with a non-combustible and non-conducting material, such as plaster of Paris or asbestos fiber, as shown at 18, and the strip 16 is embedded in this filler and extends lengthwise through the same, its 15 length being such that it has its ends projecting from the ends of the shell. The projecting end portions of the fusible strip are adapted to be placed between the ends of the heads composed of the sections 5^a and 6^a,
- 20 the sections 6^a having shallow end recesses 19 to seat the strip ends. The ends of the strip 16 are bent laterally on the outside of the heads, so that when the terminal caps 11 and 12 are applied the screws 13 may come 25 in contact with said ends. One end of the strip 16 projects a sufficient distance so that it may also be bent over against the side of the head section 6^a at the corresponding end of the holder, said section having an external side groove 20 to seat this portion of the strip, the offset position of the pin 14 on this section permitting the groove to be made therein. The enclosed portion of the fusible strip 16 has perforations 21, and its last 30 described end is marked to indicate the rating or current capacity of the fuse, the casting 6 adjacent to the head section 6^a which has the groove 20 being correspondingly marked. It is to be understood that a fusible 35 element designed for the current capacity indicated on the holder should be selected, and as this is indicated on the strip 16 it is made impossible, when ordinary care is exercised, to overload the fuse.
- 40 45 A fuse holder constructed as hereinbefore described is simple and efficient, and after

the parts are properly assembled there is nothing to get loose or out of order. When the fuse blows, the holder can be readily taken apart for renewing of the fusible element, it being necessary only to take off the terminal caps 11 and 12, after which the sections 5 and 6 can be separated. The cap 11 has a blade 11^a so that the holder can be used in connection with a knife switch.

50 55 I claim:

1. A fuse-holder comprising an elongated tubular casing which is in two longitudinal and similar separable sections, heads of conducting material on the ends of the casing, 60 said heads being also in sections, terminal caps slidably and removably fitted over the heads for coupling the casing sections together, the caps having angular slots and the head sections having projecting side pins 65 adapted to enter said slots, the pins of the respective head sections being positioned obliquely relative to each other, contact screws carried by the caps and having their inner ends located opposite the ends of the heads, and a fusible element held between the casing sections and having end portions 70 extending between the head sections and projecting therefrom to extend across outer ends of said head sections for engagement 75 by the contact screws.

2. A fuse-holder comprising an elongated tubular casing which is in two longitudinal and similar separable sections, heads of conducting material on the ends of the casing, 80 said heads being also in sections, terminal caps slidably and removably fitted over the heads for coupling the casing sections together, contact screws carried by the caps and having their inner ends located opposite the ends of the heads, and a fusible element in the casing and having end portions 85 extending between the head sections and projecting therefrom for engagement by the contact screws.

90 In testimony whereof I affix my signature.
HALL GOODWIN.
